[57] ABSTRACT

A machine for pulling and lasting a shoe upper has a plate for applying cement to an insole of the shoe having a knurled surface for applying the cement to forepart side portions of the insole and channels for applying the cement to toe portions of the insole. The machine also has wipers for pressing marginal portions of the upper forepart against the insole portions to which the plate has applied cement, including asymmetrically curved heelward portions of the insole forepart. Grippers adjacent the heelward portions of the insole forepart grip adjacent marginal portions of the upper and move downwardly and twistingly of a last over which the upper is positioned to tension the upper about the last. A control responsive to a left or right shoe orientation of the machine then causes only one of the grippers at the inside of the right or left shoe to additionally move inwardly and then upwardly relative to the last to further position and tension the upper.

PULLING AND LASTING MACHINES

BACKGROUND OF THE INVENTION

This invention relates generally to shoe upper forming machines and, more particularly, to a machine for performing a pulling and lasting operation in the entire forepart region of the shoe.

Until recently, machines for lasting shoes have been limited in operation to a particular portion of the shoe. Early efforts at combining the functions of the various machines then required to last an entire shoe forepart led to complex and expensive machines.

United States Letters Patent No. 3,099,846 issued Aug. 6, 1963 in the names of H. Lane et al describes a prior effort at simplifying the design and reducing the cost of a machine for lasting toe, forepart and ball regions of a shoe. In the machine described in the patent an upper and an insole are positioned on a last and supported at the forepart of the insole on a support of the machine. Grippers positioned about the supported last grip the upper and pull it over the last and toward edges of the last adjacent the insole.

A cement applying plate having a surface conforming to the shape of the insole on the last in both the peripheral outline of the insole and the surface or planar configuration of the insole on the last was later added to the machine. The conformed surface of the insole engaging plate was positioned to have its insole engaging surface parallel to the insole at each point corresponding to the insole on the last. The plate was then removed toward the insole simultaneously to engage the insole over the entire insole engaging surface of the plate. A single channel formed about peripheral portions of the insole engaging surface and having an open side in the surface was then supplied with cement to form a bead of cement about the peripheral portions of the insole engaged with the open side of the channel. The cement applying plate was then withdrawn and wipers engaged marginal portions of the upper with the adhesive bead on the marginal portions of the insole to secure the upper to the insole.

While the machine described has been satisfactory, it has been desired to improve the application of cement to the insole, particularly at the heelward portion of the forepart of the insole.

Copending United States Patent application Ser. No. 308,694 filed Nov. 22, 1972 in the names of Garner et al describes still further improvements to the machine of the above patent. Particularly, an improved plate for applying cement to the heelward portion of an insole forepart and improved gripper action for drawing an upper toward the insole in the heelward portion of the forepart are shown. However, the disclosed machine has no provision for accommodating the differing asymmetrical inside and outside peripheral and planar curvatures of the heelward portion of insole foreparts for wiping the upper against the insole in this region. There is also no means in the machine of the copending application for further improving the application of cement in the toe portion of the insole.

SUMMARY OF THE INVENTION

Accordingly, it is an object of the invention to provide a machine having both shoe upper tensioning and wiping means asymmetrically operable in correspondence with the asymmetrical curvatures of the heel-

ward portion of the forepart region of shoe insole and for improved cement application in the toe region of the insole.

To this end, a machine for pulling and lasting a shoe upper about a last is provided with a pair of grippers for engaging inside and outside marginal portions of an upper in a heelward portion of the shoe forepart having different operative movements for tensioning the upper about a last over which it is positioned according to the differing inside and outside curvatures of the corresponding portion of the last. A control, preferably responsive to a left or right position of a shoe heel rest of the machine indicative of the relative inside and outside curvatures of left and right shoes, controls the differing gripper movement. Means, preferably self adjusting, act on a flexible wiper of the machine to conform the wiper to the differing planar curvatures of the heelward portion of the insole forepart to improve wiping of the upper against the insole in this heelward portion. A cement applying plate having grooves extending transversely across a portion of the plate engaged with a toe portion of the insole improves the application of cement to the insole toe portion.

DESCRIPTION OF THE DRAWINGS

A preferred embodiment which is intended to be illustrative of and not a limitation on the invention will now be described with reference to drawings, in which:

FIG. 1 is a plan view of a portion of a pulling and lasting machine including the embodiment;
 FIG. 2 is a side view of a portion of a wiper shown in FIG. 1;
 FIG. 3 is a side view of a portion of the machine shown in FIG. 1;
 FIGS. 4 and 5 are side views of different positions of a gripper shown in FIG. 1; and
 FIG. 6 is a view of a toe band portion of the machine in FIG. 1.

DESCRIPTION OF THE PREFERRED EMBODIMENT

The illustrative machine including the preferred embodiment of the invention as shown in FIG. 1 is a shoe upper conforming machine suitable for use in both pulling and lasting a shoe upper in the toe and ball regions and forepart portion of a shoe, i.e., that part of an insole extending from the toe to the part where the shoe bottom curves heightwise of the generally flat portion of the forepart into the shank portion. The machine has a support generally at 2 for supporting the forepart of an insole positioned on the bottom of a last having an upper mounted over the last. For tensioning the upper about the last, the machine has a plurality of upper forepart grippers generally designated 4, 6 and 8 disposed around the shoe support means. After tensioning the upper with the grippers, a pair of toe embracing wipers generally designated 12 move from the illustrated spaced apart position heelwardly and toward each other to wipe marginal portions of the upper inwardly across edges of the insole. Additional ball region wipes are each mounted on a ball lasting unit generally designated 20. Finally, a heel support generally designated 28 restrains the shoe and last against a heelward thrust imparted by the action of the toe embracing wipers. As so far described, the machine is gener-

ally similar to that disclosed in the above identified U.S. Pat. No. 3,099,846.

Further, the grippers generally designated at 8 and commonly called the No. 2 forepart grippers are similar in construction and function to those described in the above identified copending patent application. In particular, these grippers are designed to draw the upper downwardly over a last on which the upper is positioned, inwardly of the last, and to twist the upper into conformity with a peripheral curvature of an insole on the last, all in the heelward portion of the forepart of the upper. However, in the machine in this invention, both grippers generally designated 8 do not perform all these motions in the forming of a single shoe upper, as is explained below. Further distinctions from the machine of the above patent and application will also be described.

In general, this embodiment has a heel support variably positioned for receiving right or left shoes and thereby indicating the side of the inside or outside curvatures of the shoe. Cement is applied to the insole. The grippers then tension the upper over the last using different movements on the differing inside and outside peripheral curvatures of the shoe. The wipers then wipe marginal portions of the upper against corresponding marginal portions of the insole including at the asymmetrical planar curvature of the heelward portion of the insole forepart.

FIG. 1 shows the heel support 28 mounted on a member 30 having a pivot lug at each end received in a U-shaped member 32. As seen in FIG. 3, the pivotal connection of the members 30 and 32 may be by receipt of the lugs of the member 30 in a U-shaped boss in the member 32 with the lugs retained in the boss by a bolt 34 projecting through the ends of the boss. A number of such U-shaped bosses may be vertically disposed along the end of the member 32 to provide heightwise adjustment of the heel support relative to a shoe on a last L positioned in the machine on a portion of the shoe support 2.

The member 32 is slidably supported by a bolt 35 extending through a slot in a member 36. Springs 38 are stretched between lugs of the member 32 and lugs of the member 36 to urge the member upwardly until the bolt 35 engages a movable shaft 40 of a diaphragm thruster 42 (not shown in FIG. 1). When the wipers engage the shoe, as later explained, they impart a heelward force to the shoe which may dislodge it from the heel support. To compensate for such force, the thruster 42 is simultaneously activated with the wipers to drive the shaft 40 downwardly, carrying with it the abutting bolt 35 and connected heel support 28. The added force of the thruster retains the shoe firmly in the heel support.

The member 36 has a T-headed portion slidably received in an undercut channel of a member 46 for sliding movement normal to the plane of FIG. 3 or transverse to the last L in the machine. A spring loaded friction member 48 normally holds the member 46 against such sliding movement, except as urged by a double-acting piston and cylinder 50 the movable piston of which is connected through pivoted lever 52 to a post 54 of the member 36 extending through a slot in the channeled member 46. Further, the member 46 is slidably mounted in a frame 56 of the machine to which a piston of a piston and cylinder combination (not shown) carried by the member 46 is connected for slid-

ing the member 46 relative to the frame and lengthwise of the last.

Returning to FIG. 1, a pair of stops 56 are seen to be positioned on either side of the pivoted lever 52 for limiting movement of the lever. A control, not shown, is effective to cause the piston and cylinder 50 to drive the lever 52 into engagement with one or the other of the stops 56 in each operative position of the machine. Preferably, the control alternates the lever between engagement with each stop. In this way the heel support 28 operatively connected to the lever 52 is shifted alternately between a left and right position for operating alternately on left and right shoes, respectively. In an alternative embodiment, a switch may be provided for controlling the piston and cylinder 50 to its left or right shoe condition.

FIGS. 1 and 3 also show another U-shaped member 60 having roller insole engaging members 62 on tines of the U and receiving a pivot shaft 64 through a bridge 20 of the U between the tines. The U-shaped member 60 freely rotates on the shaft 64. The shaft 64 extends from one end of a lever 65 the other end of which is connected to a piston and cylinder 66 for swinging the lever about a pivot intermediate its ends, as best seen 25 in FIG. 3. In an inoperative position the rollers 62 are oriented below the plane of the wipers 12, and below the heelward portion of the forepart of a shoe on the last L located in the machine. After the grippers have 30 tensioned the upper about the last and a cement applying surface of a cement applying plate 72 (FIG. 1) has applied cement to an insole positioned on the last, the wipers 12 move heelward of the last at least to the heelward portion of the forepart and close inwardly of the last to wipe marginal portions of the upper against marginal portions of the insole in the well known manner. However, in the heelward portion of the forepart, the insole departs from its generally planar orientation in 35 the toe region and curves upwardly as seen in FIG. 3. Moreover, the planar curvature of the insole often is different or asymmetrical from the inside to the outside sides of the insole. In addition, the curvature changes from one style of shoe to the next. Accordingly, no one orientation of the wipers appropriate for the planar curvature may be made for accommodating even a single pair of shoes let alone different shoe styles.

When the wipers 12 have moved to the heelward portion of the forepart and closed inwardly of the last to wipe the upper against the insole, the piston and cylinder 66 pivots the lever 65 to raise the rollers 62 at the 40 opposite end of the lever into engagement with the wipers to bend the wipers into engagement with the insole. When the wiper on the least curved side of the shoe, usually the outside, engages the insole, the U-shaped member 60 pivots on the shaft 64 to continue bending the other, usually inside, wiper into engagement with the insole. This pivoting movement of the member 60 45 equalizes the pressure of the wipers on the inside and outside of the shoe to uniformly press marginal portions of the upper on both sides of the shoe against the insole.

In order to insure appropriate wiping of the upper against the insole, the wipers 12 are usually substantially rigid. Such rigid wipers may not be appropriately deflected by the member 60 to engage the insole. Accordingly, each wiper 12 is provided with a slot 74 (FIG. 1) extending into the wiper from the portion 55 engaging the heelward portion of the insole forepart a

convenient distance. In addition, portions 76 of the wipers adjacent the slot 74 are made thinner than the remaining wiper, as seen in FIG. 2. The thinned wiper section is then stiffly flexible to be deflected by the rollers 62 on the member 60 into engagement with each side of an insole on the last.

Further improved wiping action, as well as tensioning of the upper about the last, is achieved with the pair of grippers 8. FIG. 4 illustrates one of the two identical such grippers. A gripper member 80 is fixedly mounted on a body member 82 and a second gripper member 84 pivoted on the body member for gripping a marginal portion of the upper between the gripper members 80 and 84. For such gripping, the pivoted gripper member 84 is operatively connected to a piston and cylinder 86 in the body of the gripper for pivotal movement toward and away from the gripper member 80.

The body member 82 is pivotally mounted on a frame 88 of the machine by a link 90 pivotally connected at each end to the frame and the body member. At an end of the body member opposite the gripper members 80 and 84 a bell crank 92 pivotally connects the body member to two pistons and cylinders 94 and 96. A further piston and cylinder 97 swings the gripper normal to the plane of FIGS. 4 and 5 as described in the co-pending application.

In operation of the gripper 8 the piston and cylinder 86 first operates to grip a marginal portion of the upper between the gripper members 80 and 84. The piston and cylinder 94 then operates to raise the connected end of the gripper body 82 while retaining the bell crank 92 in the position relative to the body member shown in FIG. 4. The gripper members at the opposite end of the body member then move downwardly as seen in FIG. 5. The piston and cylinder 96 may then be extended to swing the bell crank 92 from the position shown in FIG. 4 to the position shown in FIG. 5. The pivotal movement of the bell crank 92 drives the body member and connected gripping members 80 and 84 to the left as seen in FIG. 5, inwardly of the last. A twisting action as described in the above recited copending patent application may also occur.

During inward movement of the gripper, the gripper members 80 and 84 may be raised toward the underside of the last by a slight cooperative retraction of the pistons and cylinders 94 and 96 while retaining the relative orientation of the bell crank 92 to maintain the gripping members 80 and 84 in their inward position. Such raising of the gripper members 80 and 84 presses the marginal portion of the upper against the insole on the last in a wiper-like action to enhance the pressing of the upper against the insole with the gripping members 80 and 84. The gripping member 84 is provided with an extended, substantially flat surface 98 substantially parallel to the insole on the last when the grippers are in their innermost extended position.

To appropriately accommodate the differing, asymmetrical planar curvature of the inside and outside sides of a shoe, only one of the grippers 8 preferably carries out the above described sequence of movements. The other gripper merely grips the upper and moves downwardly of the last by action of the cylinder 94, the bell crank 92 then being in the orientation relative to the body member 82 shown in FIG. 4. Twisting movement of the grippers may be carried out by either or both of the grippers, again as recited in the above identified patent application.

In operation, the outside planar curvature of an insole in the heelward portion of a shoe forepart is small as compared to the planar curvature of the inside side of the heelward portion of a shoe forepart. Accordingly, it is preferably desirable to have the gripper 8 on the inside side of a shoe carry out the complete sequence of gripping, downward, inward, twisting and upward movements, thereby pressing the upper against the more curved heelward portion of the forepart insole which curve brings the insole substantially above the general plane of the toe portion of the insole. In contrast, the gripper 8 adjacent the outside side of the shoe preferably grips the upper and moves only downwardly and twistingly to draw the upper toward the outside heelward portion of the shoe forepart less curved out of the toe plane of the insole than the inside. For the purpose, the control (not shown) which determines the left and right position of the heel support 28 also appropriately activates the pistons and cylinders 94 and 96 to provide the inside and outside grippers 8 each with the downward movement but only the inside one of the grippers 8 with the additional inward and upward movements. Alternatively, manually operable switches may be provided for appropriately operating the inside and outside grippers 8.

Returning to FIG. 1, the toe portion of the cement applying plate 72 is seen to have a plurality of transverse channels 101 each having a cement dispensing port 102 for supplying the communicating channel with cement from a cement dispensing passageway (not shown) internal the plate. The channels 101 cover the entire area of the toe portion of the plate 72 and do not extend merely peripherally along the toe in a manner generally known for cement applying plates. The channels thereby apply cement to a substantial area of the insole in the toe region of the insole rather than in a single beading along the periphery of the toe portion. The transverse beads of cement laid down by each of the transversely oriented channels 101 aids in spreading the cement over the toe portion of the shoe when the wipers move heelwardly of the shoe to wipe the upper against the insole inasmuch as the heelward movement of the wipers is normal to the transverse orientation of the cement beads.

Finally, FIG. 6 shows a toe band arrangement having a toe band 264 generally of horseshoe-shaped outline roughly corresponding to the toe and forepart shape of a shoe. Two brackets 256 having arms 257 extend from a portion 269 of the wiper frame toward the shoe support generally at 2. Each of the arms has a block member 258 supporting the toe band 264 for distributing pressure applied to the band during operation of the toe band. The frame portion 269 is mounted for movement heelward of the shoe to engage the toe band with the shoe on a last L on the shoe support. Further movement of the toe band is provided by two piston and cylinder arrangements 259 each connected to one of the brackets 256 for further moving the toe band into engagement with the shoe. A further piston and cylinder arrangement 260 operatively engages the toe band at the extreme toe end of the shoe with a pad 262 to further conform the band to the shoe. Toward the ends of the horseshoe-shaped toe band are two pairs of clamping blocks 266 and 268 one of each pair being arranged on an opposite side of the band from the other of the pair. Four piston and cylinder arrangements 270 mounted on an extension 271 of the frame 269 moves

the blocks 266 and 268 to firmly engage the band 264 with the shoe to hold the upper against the last after the grippers have completed their operation and before the wipers move to press the marginal portions of the upper against the insole. Bases 272 of each block 268 are machined to form a curved surface to more accurately press the toe band to the contours of the heelward portion of the forepart of the shoe, especially at the more curved inside side of the shoe.

Having thus described our invention what we claim is:

1. A machine for forming a shoe upper about a last having means for tensioning the upper over the last and means for wiping marginal portions of the upper against corresponding marginal portions of an insole also on the last wherein the tensioning means comprise:

a gripper for gripping a marginal portion of the upper and movable downwardly and inwardly of the last for tensioning the upper over the last, which gripper is additionally movable upwardly of the last during its inward movement for engaging the upper with the insole and means for so moving the gripper.

2. A machine as in claim 1 wherein the gripper has 25

a gripping member having a generally flat surface portion for pressing the upper against the insole.

3. A machine as in claim 1 additionally comprising: a pair of the grippers one adjacent an inside side of the shoe and one adjacent an outside side and means for moving the outside gripper only downwardly of the last.

4. A machine as in claim 3 additionally comprising a heel support movable from a right to a left shoe position indicative of the inside and outside sides of the shoe and wherein the gripper moving means are responsive to the heel rest position for determining the inside and outside gripper movement.

5. A machine for forming a shoe upper about a last having means for tensioning the upper over the last and means for wiping marginal portions of the upper against corresponding marginal portions of an insole also on the last comprising: a cement applying surface of a plate engageable with the insole having a plurality of channels transverse of a portion of the surface engageable with a toe portion of the insole for applying a plurality of transverse beads of adhesive to the toe portion of the insole and means inside the plate for supplying cement to the channel.
